UNITED STATES PATENT OFFICE.

GEORGE H. NEIDLINGER, OF EAST ORANGE, NEW JERSEY.

DESIGN FOR A CHRISTMAS-TREE ORNAMENT.

60,201.

Specification for Design.

Patented Jan. 10, 1922.

Application filed February 2, 1921. Serial No. 442,003. Term of patent 7 years.

To all whom it may concern:

Be it known that I, GEORGE H. NEIDLINGER, a citizen of the United States, residing at East Orange, in the county of Essex and State of New Jersey, have invented a new, original, and ornamental Design for Christmas-Tree Ornaments, of which the following is a specification, reference being had to the accompanying drawing, forming a part thereof.

Figure 1 is a view in side elevation of my original design for an ornament.

Figure 2 is an end of Figure 1.

I claim:

The ornamental design for a Christmas tree ornament, as shown.

GEORGE H. NEIDLINGER.
